UNITED STATES PATENT OFFICE.

CHARLES F. MURDOCK, OF DETROIT, MICHIGAN, ASSIGNOR TO THE AUTOMATIC CAR COUPLER HEATING COMPANY, OF MICHIGAN.

PIPE-COUPING.

SPECIFICATION forming part of Letters Patent No. 416,230, dated December 3, 1889.

Application filed June 24, 1889. Serial No. 315,436. (No model.)

To all whom it may concern:

Be it known that I, CHARLES F. MURDOCK, a citizen of the United States, and a resident of Detroit, in the county of Wayne and State 5 of Michigan, have invented new and useful Improvements in Couplers; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to means for coupling and uncoupling pipe or hose attached to railway-cars; and it consists in the novel construction and arrangement of devices, as hereinafter specified and claimed.

In my application filed February 11, 1889, 15 Serial No. 299,387, I have illustrated and described a coupling to which the present invention is an improvement. In my said application No. 299,387 the uncoupling is effected by means of ropes attached, respectively, to 20 the handles of the coupler and railway-cars.

I find by experiment that the use of ropes alone for the purpose is not entirely free from objection, because such ropes are liable to shrinkage and to stretching, so that they may 25 become either too short or too long and be partially inoperative.

In the drawing, the figure represents my improved couplings, in which the letter I indicates a pipe or hose, and H^2 an iron tube 30 attached rigidly to a railway-car.

The letter H represents an iron rod, to which is attached a short chain H^2 , which said chain is connected with a collar arranged around the pipe, as shown at a. The opposite end of 40 this chain is connected with the rod H, which said rod extends to and is connected with a pendent hanger pivoted at c on the coupling. The pivotal point of this hanger or trip is a stud or pin projecting from the side of the 45 coupling, and in my application No. 299,387 is called a "trunnion," provided with an anti-friction roller. My present invention con-

sists, in part, in forming such roller with an extended arm that passes downward and is connected with the rod H, as shown at C. The 50 arm of this trip or hanger is marked B.

It will be observed that my rods and chains are arranged in duplicate form, one on each side of the coupling proper. The same is true of the trip C' and collars H'.

The letters D and D' represent levers extending downward from handles (marked 35) and clasping-trunnions (marked a a') on the coupling. It will be observed that said lever D not only partially clasps the trunnion a, 60 but also at its lower end bears against the side of trip B.

In operation, when it is desired to uncouple the pipe or hose automatically, the coupling is removed from between the two cars to 65 which my device is attached, and as the forward car is moved, the hose is gradually drawn up from its center or coupling-point, the trips B are made to release the clasp of the lever extending from the handle, and the 70 uncoupling is accomplished. It is obvious that this is performed because the rods H and their connections are less in length than the section of the hose with which they are connected.

In practice I sometimes dispense with the use of chains on the ends of the rods; but as a rule I prefer to use the chains, because they are better for the movement of the cars.

What I claim, and desire to secure by Letters Patent, is—

The combination, with a pipe or hose I and trip B, pivoted thereto, of a lever D, bearing against the trip, pipe H', secured to a car-collar c surrounding the same, and a combined rod and chain H, secured at one end to the trip and at the other end to the collar c, as set forth.

In testimony whereof I affix my signature in presence of two witnesses.

CHARLES F. MURDOCK.

In presence of—

THOMAS T. LEETE, Jr.,
JOS. L. HARRINGTON.
